UNITED STATES PATENT OFFICE.

EDWIN M. ROSENBLUTH, OF PHILADELPHIA, PENNSYLVANIA.

DESIGN FOR A VEHICLE NUMBER-PLATE SUPPORT.

41,388.

Specification for Design.

Patented May 16, 1911.

Application filed March 2, 1911. Serial No. 611,943. Term of patent 14 years.

To all whom it may concern:

Be it known that I, EDWIN M. ROSENBLUTH, of Philadelphia, in the State of Pennsylvania, have invented a new, original, and ornamental Design for Vehicle Number-Plate Supports, whereof the following is a specification, reference being had to the accompanying drawing.

In the drawing; Figure I is a plan view

of a support showing my design and Fig. II is a front elevation of said support.

I claim—

The ornamental design for a vehicle number plate support, as shown.

EDWIN M. ROSENBLUTH.

Witnesses:

G. W. K. VOIGT,
H. C. ROSENBLUTH.
